COIN CONTROLLED VENDING APPARATUS

Clarence A. Friemering, Dayton, Ohio

Application June 1, 1939, Serial No. 276,844

6 Claims. (Cl. 194—57)

This invention relates to a coin controlled vending apparatus and more particularly to an apparatus for vending articles at a price requiring the insertion of a plurality of coins in the vending apparatus. It has been proposed heretofore to provide vending machines with multiple coin controlled mechanism but these mechanisms, for the most part at least, have been of a more or less complicated and expensive character and were not suitable for use in a vending machine which must be of a simple inexpensive construction, such for example as a newspaper vending machine.

One object of the invention is to provide a multiple coin controlled mechanism which will be simple in construction, positive in operation and inexpensive to construct.

A further object of the invention is to provide such a mechanism in which the coin chute moves with the ejector and the ejector lock is controlled in accordance with the number of coins in the chute.

A further object of the invention is to provide a simple and efficient vending apparatus embodying such a control mechanism.

Other objects of the invention may appear as the apparatus is described in detail.

In the accompanying drawing Fig. 1 is a sectional view of a vending apparatus embodying my invention, taken on the line 1—1 of Fig. 2; Fig. 2 is a sectional view taken on the line 2—2 of Fig. 1; Fig. 3 is a transverse sectional view taken on the line 3—3 of Fig. 2; and Fig. 4 is a detail view of the chute and controlling rods, partly broken away.

In the drawing I have illustrated one embodiment of my invention and have shown the same as embodied in a newspaper vending machine. It will be understood, however, that the controlling mechanism may be applied to vending apparatus of various kinds and may take various forms without departing from the spirit of the invention.

The particular apparatus here illustrated comprises a cabinet 5 having a hinged closure 6 at its top and divided by a vertical transverse partition 7 into two compartments, the compartment 8 constituting a magazine for the articles to be vended and the compartment 9 containing the control mechanism. The article compartment 8 is provided at its lower front end with a discharge opening 10 through which articles are ejected and this opening is provided with a guard 11 to insure the delivery of a single article and to prevent the insertion of a

hook or other implement by means of which the articles might be withdrawn.

The articles may be ejected, or discharged, from the apparatus by an ejector of any suitable kind and in the construction illustrated the ejector comprises a flat plate 12 slidably mounted in the lower part of the cabinet and provided with means for actuating the same, in the present instance a pull rod 13 extending beyond the discharge opening 10 and having a handle portion 14. The bottom of the cabinet is provided with a groove in which the pull rod is mounted and this groove extends rearwardly beyond the pull rod and a spring 15 is mounted in this rear portion of the groove and connected at one end with a stud 16 secured to the ejector plate 12 and secured at its other end to a stud 17 mounted at the rear end of the groove, the spring serving to return the ejector to and to retain the same in its normal or retracted position. The ejector plate is provided with an upwardly extending projection or lip 18 of such a height that it will pass beneath the lower edge of the partition 7, which is spaced a short distance from the bottom of the cabinet, and will engage the lowermost article only and will eject that article through the opening 10 when the ejector is moved to its foremost or ejecting position. The ejector may be such as to completely discharge the article from the apparatus but in vending articles such as newspapers the article is moved by the ejector only far enough to enable the projecting end thereof to be grasped by the purchaser.

Mounted within the control chamber 9 is a coin chute 19 which is connected with the ejector for movement therewith and, in the present instance, is rigidly mounted on the ejector plate 12, as by means of an upright supporting structure or plate 20. One side wall of the cabinet is provided with a coin inserting opening 21 so arranged that when the ejector is in its normal position one end of the chute will be in line with the opening 21 and adapted to receive coins therefrom. This coin chute is adapted to receive a plurality of coins and means are provided for retaining the coins in the chute until they are released by the operation of the control mechanism. Means are provided for locking the ejector normally against movement to its ejecting position and this means includes a part so arranged that when the chute contains a predetermined number of coins the coin last inserted will engage and actuate this part of the locking mechanism, when initial movement is im-

parted to the ejector, so as to release the ejector for movement to ejecting position. In the particular arrangement here shown the coin chute 19 is supported in an inclined position and is provided in its upper edge and near the lower or discharge end thereof with a notch 22. A rod 23 is pivotally mounted on a fixed axis in the rear of the coin chute, in the present instance on pivot lugs 24 mounted on the end wall of the cabinet, and this rod extends forwardly and downwardly through the opening 22 so that it lies in the path of the coins in the chute 19 and will be engaged by the lowermost of said coins so as to retain all the coins in the chute. 5

10 This rod is retained normally in its operative position by gravity and is provided with means whereby it will be moved out of the path of the coins, to release the same, as the ejector approaches the end of its ejecting movement. In the present instance the free end portion of the rod is flattened and widened, as shown at 25, so that as the coin chute moves forwardly with the ejector this widened portion of the rod will be moved out of the notch and onto the upper 15 edge of the chute, thus moving it out of the path of the coins, and when the coin chute returns to its normal position the rod will automatically return to its operative position by gravity. 20

The coin chute 19 is also provided in its upper edge with a second notch 26 which is spaced such a distance from the notch 22 that when a predetermined number of coins 27, in the present instance three pennies, are inserted in the chute and their movement arrested by the rod 28 the uppermost coin, that is the one last inserted, will extend across the notch 26 and its upper edge will be exposed through that notch. A locking member, or members, is secured to the ejector for movement therewith and, as here 25 shown, these members comprise two forwardly facing hook-shaped elements 28 spaced a short distance one from the other. Cooperating with these locking members is a second or locking rod 29 which is pivotally mounted at one end on an axis in the rear of the coin chute, such as the pivot lugs 30 secured to the rear wall of the cabinet. This rod extends forwardly and downwardly across the chute 19 directly above the notch 26. This rod is provided at its lower end 30 with a cross member, or T-head, 31, which, when the chute is in its normal position, will rest upon the ejector plate 12 in line with the hook shaped locking members 28, the longitudinal portion of the rod being arranged between these members, so that forward movement of the ejector while the locking rod is in its normal position, will result in the hook shaped members 28 engaging over the respective ends of the T-head 31, which will positively interrupt the forward or ejecting movement of the ejector before the lip 18 thereof has moved far enough to displace the lowermost article in the article compartment. It will be noted from Fig. 2 that when the parts are in their normal positions the T-head 31 of the locking arm is placed some little distance in front of the locking members on the ejector and when the predetermined number of coins has been inserted in and retained in the coin chute, with the last coin extending across 35 the notch 26, the initial movement of the chute with the ejector will cause the upper edge of the coin last inserted to engage the locking rod 29 and move the T-head thereof to an elevated position out of the path of the locking members before the latter have had an opportunity to

engage the same, thus releasing the ejector for ejecting movement and permitting the same to be moved to the limit of its movement to eject the article. It will be obvious that if there is no coin in the chute or if less than the predetermined number of coins has been inserted therein the rod 29 will enter the notch 26 as the chute moves forwardly with the ejector, thereby permitting the hook shaped locking members to engage over the T-shaped head of the locking arm and lock the ejector against further movement before the locking arm can engage and be actuated by the lower edge of the notch. The forward movement of the ejector, after it has been released, is limited by a stop 32 secured to the ejector plate and arranged to engage a stop 33 fixed to the cabinet. Just before the end of the ejecting movement of the ejector the wider portion 25 of the retaining arm 23 will engage the upper edge of the chute and release the coins and permit the latter to be discharged from the chute into a suitable coin receptacle, which is here shown as a box 34 mounted on the ejector plate for movement therewith so that it is at all times beneath the discharge end of the chute. 20

While I have shown and described one embodiment of my invention I wish it to be understood that I do not desire to be limited to the details thereof as various modifications may occur to a person skilled in the art. 30

Having now fully described my invention, what I claim as new and desire to secure by Letters Patent, is:

1. In a vending apparatus, a cabinet having means to support articles to be vended, an ejector mounted in said cabinet for forward ejecting movement, means for actuating said ejector, a gravity coin chute connected with said ejector for movement thereby and having at its upper end a coin receiving opening and having at its lower end a coin discharge opening, means adjacent said discharge opening to retain coins in said chute when said chute is in its rearmost position and to release said coins when a predetermined forward movement has been imparted to said chute, a locking member carried by said ejector in front of said chute, said chute having an opening spaced such a distance from said retaining means that when a predetermined number of coins has been inserted in said chute the coin last inserted will extend across the last mentioned opening, a second locking member movably mounted on a fixed support in said cabinet and having a locking part which normally cooperates with the first mentioned locking member to prevent ejecting movement of said ejector, said locking member also having a second part spaced from said locking part and positioned in front of said chute to be engaged and actuated by said last coin to move said locking part to an inoperative position when said chute is moved forwardly with said predetermined number of coins therein and to extend through said opening in said chute with said locking member in its operative position when said chute is moved forwardly with less than said predetermined number of coins therein. 45

2. In a vending apparatus, a cabinet having means to support articles to be vended, an ejector mounted in said cabinet for forward ejecting movement, means for actuating said ejector, a gravity coin chute connected with said ejector for movement thereby and having at its upper end a coin receiving opening and having at its 70

lower end a coin discharge opening, means adjacent said discharge opening to retain coins in said chute when said chute is in its rearmost position and to release said coins when a predetermined forward movement has been imparted to said chute, a locking member carried by said ejector in front of said chute, said chute having in one edge thereof a notch spaced such a distance from said retaining means that when a predetermined number of coins has been inserted in said chute the coin last inserted will extend across said notch, a rod pivotally mounted on a fixed axis in the rear of said chute, extending forwardly across said chute and having at its forward end a locking part which normally cooperates with said locking member to prevent ejecting movement of said ejector, said rod also having an inclined part arranged in front of and adjacent to said notch to be engaged and actuated by the coin extending across said notch to move said locking part to an inoperative position when said chute is moved forwardly with said predetermined number of coins therein and to enter said notch without moving said locking part when said chute is moved forwardly with less than said predetermined number of coins therein.

3. In a vending apparatus, a cabinet having means to support articles to be vended, an ejector mounted in said cabinet for forward ejecting movement, means for actuating said ejector, a gravity coin chute connected with said ejector for movement thereby and having at its upper end a coin receiving opening and having at its lower end a coin discharge opening, a retaining member movably mounted on a fixed support in said cabinet and having a part which extends into the path of the coins in said chute when said chute is in its rearmost position, said member having a second part spaced forwardly from the first mentioned part to be engaged and actuated by said chute to move said first mentioned part out of the path of said coins when a predetermined forward movement has been imparted to said chute, a locking member carried by said chute, said chute having an opening spaced from said retaining member such a distance that when a predetermined number of coins has been inserted in said chute the coin last inserted will extend across the last mentioned opening in said chute, a second locking member movably mounted in said cabinet on a fixed support, having a locking part which normally cooperates with the first mentioned locking member to prevent ejecting movement of said ejector and also having a part arranged in front of said chute to be engaged and actuated by the coin which extends across said last mentioned opening to move said locking member to an inoperative position when said chute is moved forwardly with said predetermined number of coins therein.

4. In a vending apparatus, a cabinet having means to support articles to be vended, an ejector slidably mounted in said cabinet for forward ejecting movement, means for actuating said ejector, an inclined coin chute connected with said ejector for movement thereby and having at its upper end an opening through which coins may be inserted therein and having at its lower end an opening through which said coins may be discharged, a rod pivotally mounted on an axis fixed with relation to said ejector, extending normally across the lower portion of said chute in the path of the lowermost coin in said chute and having a part in front of said chute arranged to

be engaged and actuated by said chute to move said rod out of the path of said coins when said chute is moved forwardly by said ejector, a locking member carried by said ejector, and a second rod pivotally mounted on an axis fixed with relation to said ejector and having at its free end a part which extends into the path of said locking member when said chute is in its rearmost position or contains less than a predetermined number of coins, said second rod being so arranged with relation to said chute and to the first mentioned rod that when said chute is in its rearmost position and contains said predetermined number of coins a part of said second rod will be positioned in front of and adjacent to the uppermost coin in said chute and the initial forward movement of said chute by said ejector will cause said uppermost coin to engage the last mentioned part of said second rod and move the first mentioned part thereof out of the path of said locking member.

5. In a vending apparatus, a cabinet having means to support articles to be vended, an ejector slidably mounted in said cabinet, means for actuating said ejector, an inclined coin chute connected with said ejector for movement thereby and having at its upper end an opening through which coins may be inserted in said chute and having at its lower end an opening through which said coins may be discharged, said chute having in its upper edge a notch near the lower end thereof and a second notch spaced from the first mentioned notch such a distance that when said chute contains a predetermined number of coins the coin last inserted will extend across said second notch, a rod pivotally mounted on an axis fixed with relation to said ejector, supported normally in said lower notch in the path of said coins and having a part arranged in front of said chute to be engaged and actuated by said chute to move said rod out of the path of said coins when said chute is moved forwardly a predetermined distance by said ejector, a locking member carried by said ejector, a second rod pivotally mounted on an axis fixed with relation to said ejector, extending downwardly and forwardly across said chute above and in front of said second notch and having at its lower end a part supported normally in the path of said locking member, said second rod being thus so positioned with relation to said second notch that the initial forward movement of said chute by said ejector will cause a coin extending across said second notch to engage said second rod and move said part thereof out of the path of said locking member.

6. In a vending apparatus, a cabinet having in its forward portion an article compartment and in its rear portion a control compartment, an ejector comprising a plate slidably mounted in the lower part of said cabinet with its rear portion in said control compartment and having a part adapted to engage an article in said article compartment, means for imparting forward ejecting movement to said ejector, a transversely inclined coin chute rigidly mounted on said plate in said control compartment and having at its upper end an opening through which coins may be inserted in said chute and having at its lower end a discharge opening, said cabinet having an opening registering with the upper opening of said chute when said ejector is in its rearmost position, said chute having in its upper edge a notch adjacent the discharge end thereof and a second notch spaced from the first mentioned notch such a

distance that when said chute contains a pre-determined number of coins the coin last inserted will extend across said second notch, a rod pivotally mounted on a fixed axis in the rear of said chute, extending forwardly through the first mentioned notch in the path of said coins and having a relatively wide forward part to engage the upper edge of said notch and move said rod out of the path of said coins when said chute is moved forwardly by said ejector, a hook-shaped locking member secured to said plate in front of said chute, a second rod pivotally mounted on a

fixed axis in the rear of said chute, extending forwardly and downwardly across said chute above and in front of said second notch and having at its forward end a part arranged normally in the path of said locking member, said second rod being thus so positioned with relation to said second notch that the initial forward movement of said chute by said ejector will cause a coin extending across said second notch to engage said second rod and move said part thereof out of the path of said locking member. 5

CLARENCE A. FRIEMERING.
